COMBINATION OUTER AND UNDER GARMENT

Anna T. Scruggs, Enid, Okla., assignor to Karoll's, Inc., Chicago, Ill., a corporation of Illinois

Application October 12, 1954, Serial No. 461,739

1 Claim. (Cl. 2—71)

This invention relates to female wearing apparel and has more particular reference to a combination outer and under garment for females, which is especially useful for mentally defective or mentally ill females.

An object of the invention is the provision of a novel and an improved combination outer and under garment comprising a unitary dress and panty and adapted substantially completely to clothe a wearer.

Mentally defective people are classified as mild, moderate, or severe corresponding substantially to intelligence quotients of about 70 to 85, about 50 to 70, or below 50, respectively. The last mentioned class includes mental defectives requiring custodial or complete protective care. Many of them are so severely disturbed that they are from time to time afflicted with or seized by exhibitionist or destructive impulses or both. It is difficult and expensive to keep clothes on such individuals.

When such a mentally defective or retarded female is afflicted with or seized by such impulses, she will sometimes grasp her skirt in her hands at about their normal depending level and swing them and the grasped portions of the skirt forwardly and upwardly to a level over her head. In that manner, she may either remove her dress or, by moving her upraised hands grasping the skirt laterally in opposite directions, rip or tear the skirt, or open its fastening means. At other times, she will grasp the bodice or waist of her dress in, and at opposite sides of the neck opening and pull the bodice apart. She thus indecently exposes her body and often mutilates her dress beyond repair.

Another object of the invention is the provision of a novel combination dress and panty which is so constructed as to restrain such a mentally defective female wearing the same from so exposing herself and so mutilating the garment.

Further objects of the invention include the provision of such a combination dress and panty which is so constructed as to be readily donned and doffed, as to obviate underwear as separate pieces, as to facilitate natural excretory acts without necessitating doffing the garment, as to make indecent exposure difficult, and as to resist to a remarkable degree ripping of the seams and tearing of the garment by a mentally defective female.

Other objects of the invention will appear from the following description and accompanying drawing which disclose a preferred embodiment of the invention and are illustrative thereof.

In the accompanying drawing:

Figure 1 is a front view in elevation of a combination outer and under garment embodying the features of the invention and having portions removed to bring out certain structural details;

Fig. 2 is a fragmentary, perspective view of the various parts of the garment of Fig. 1 shown separately;

Fig. 3 is a fragmentary cross-section taken substantially along the lines 3—3 of Fig. 1 and shows the seam structure securing the collar to the waist or bodice sec-

2

tion of the novel garment at the periphery of the neck opening therein;

Fig. 4 is a fragmentary cross-section of the collar, taken substantially along the lines 4—4 of Fig. 2;

Fig. 5 is a fragmentary cross-section of the bodice section of the novel garment, taken substantially along the lines 5—5 of Fig. 2;

Fig. 6 is a fragmentary cross-section of the bodice section, taken substantially along the lines 6—6 of Fig. 2;

Fig. 7 is a fragmentary cross-section of the skirt section of the novel garment, taken substantially along the lines 7—7 of Fig. 1;

Fig. 8 is a fragmentary cross-section of the novel garment, taken substantially along the lines 8—8 of Fig. 1 and showing the construction at the waistline of the garment; and

Fig. 9 shows the novel garment on a wearer and illustrates the restraining function of the crotch strap and waistline construction against raising the skirt over the head of the wearer.

Illustrative of the invention, the accompanying drawing shows a combination outer and under garment comprising a dress A and a panty B disposed within the skirt section of the dress. The garment is preferably made of a printed twill by stitching its components together.

The dress A as illustrated includes a bodice or waist section 11 having arm openings 12 and 13, and a neck opening 14 large enough to receive therethrough the head of a wearer. That bodice section is adapted to extend downwardly from the shoulders to the waistline of the garment and is made by stitching a front portion 15 and a back portion 16 together with shoulder seams 17 and side seams 18. The material about the arm openings 12 and 13 is hemmed as shown at 19 and 21, respectively.

Seams 17 and 18 are preferably of the type known as double, closed seams. They are made by folding back a marginal portion of each of the two pieces of material to be joined together so that the folded-back portion lies adjacent the main body of the material, lapsing the folded margins with the folded-back portions adjacent each other between the pieces of material and preferably, as shown in Fig. 5, in interlocking relationship, and stitching through the lapped margins along the spaced folded edges thereof. Thus the edge of neither piece of material is exposed or readily accessible and cannot be grasped in an effort to open the seam. The seams employed in the hems 19 and 21 are of the single, closed type. They are made, as shown in Fig. 6, by folding the margin of the turned under portion of the material to dispose it between that portion and the main portion of the material and sewing through the three plies of the material so arranged. In that manner, the edge of the material in neither of the hems 19 and 21 is accessible to facilitate opening the seam or tearing the material.

About the neck opening 14 is secured a collar 22 which is preferably of ring-like or circular configuration. As illustrated in Fig. 2, that collar is made from two substantially identical, semi-circular strips 23 and 24 joined by stitched seams 25 (Figs. 2 and 4) at opposite sides of a central opening 26 of substantially the same size as the neck opening 14. The collar is arranged, as shown in Fig. 1, on the bodice section 11 with the openings 14 and 26 in registration or coaxial relationship and with the seams 25 of the collar in registration with the shoulder seams 17, respectively. In that position, with the peripheral margins of the materials about the openings 14 and 26 folded to lie adjacent each other between the bodice section and collar, as shown in Fig. 3, the collar is stitched as at 27, preferably with a double seam, to the bodice section about and adjacent the registered openings 14 and 26. The outer periphery of the collar 22 is folded downwardly and back beneath the collar and secured to

the bodice section preferably by a double stitched seam 28. If desired, the outer periphery of the collar is provided with a usual decorative edging 29.

The collar is thus secured to the bodice section by closed seams to render the edges of the materials inaccessible. When the collar is so secured to the bodice section, four plies of the material about the neck opening are, as shown in Fig. 3, provided to strengthen the garment against ripping and tearing, and the closed seam 28 provides adequate resistance against tearing the collar from the bodice section.

Where the novel garment is to be used without a brassiere or a similar undergarment, it is so constructed as to cooperate with a skirt section 31 to provide a loosely fitting dress hanging in substantially straight lines from the shoulders of a wearer. Such a garment is sometimes called a sack type dress and usually is worn with a belt adapted to gather the dress about the waist of the wearer.

The illustrated dress is of the sack type and the skirt section 31 thereof comprises, as shown in Fig. 2, a pair of substantially identical, rectangular front panels 32 joined together along the front, longitudinal center of the skirt section by a double, closed seam 33, and a pair of substantially identical, rectangular rear panels 34 joined together along the rear, longitudinal center of the skirt section by a double, closed seam 35. The corresponding outer margins of the front and rear pairs of panels 32 and 34 are joined together along opposite sides of the skirt section by double, closed seams 36. The lower end or margin of the skirt section is provided with a suitable hem secured in place, as shown in Fig. 7, by a single, closed seam 37 and, if desired, a seam 37' thereto below and parallel thereto.

The panty B comprises, as shown in Fig. 1, a hip enveloping portion 38 and a crotch strap 39 for joining from front to rear the lower end of the hip enveloping portion to provide leg or thigh openings 41. As illustrated in Fig. 2, the panty is preferably constructed of a pair of front panels 42, each provided at its lower, inner side with a depending tab 43, and a pair of rear panels 44, each provided at its lower, inner side with a depending tab 45. The front panels 42 are joined together at the front longitudinal center of the panty by a double, closed seam 46 extending from the upper end of the panty throughout the length thereof and the length of the tabs 43 whereby the joined tabs 43 form a front strap portion 47.

The rear panels 44 are likewise joined together by a double, closed seam 48 whereby the joined rear tabs 45 form a rear strap portion 49. Those joined pairs of front and rear panels 42 and 44 are joined together along opposite sides of the panty by double, closed seams 51. The material about each leg opening 41 and along opposite sides of each of the strap portions 47 and 49 is provided with a hem held in place by a single, closed seam 52. After providing a hem transversely of the outer end of each strap portion 47 and 49, the hem being held in place by a single, closed seam 53, the hemmed ends of those strap portions are provided with complementary snap fasteners or other suitable fastening means 54 for detachably securing them together. When the crotch strap 39 comprising the strap portions 47 and 49 is open, the panty may be donned by pulling it downwardly about the head and body of a user, and removed or doffed by pulling it upwardly over her head. When the crotch strap is closed while the panty is being worn, the crotch strap restrains upward movement of the panty. The waist portions of the bodice section 11, skirt section 31, and panty B are about the same size.

With the panty B inside of the skirt section 31, and their upper margin adjacent each other, the lower margin of the bodice section 11 is folded outwardly and back about an upwardly adjacent portion of the bodice section and is arranged inwardly adjacent the upper margin of

the panty. See Fig. 8. In such relative positions, the bodice and skirt sections 11 and 31 and the panty B are stitched together along a seam 55 extending entirely around the novel combination garment at the waistline thereof, with their lapped margins at the outside of the garment. An elastic belt 56 is arranged about the waistline of the garment and is enclosed between it and a cloth strap 57, also encircling the garment at the waistline thereof. The cloth strap 57 is joined along its upper margin to the bodice section 11 by an encircling seam 58 of stitches above the seam 55 and to the skirt section 31 and panty B by an encircling seam 59 of stitches below the seam 55. The seams 58 and 59 are of the single, closed type. Thus the waistline strap 57 not only conceals the elastic belt 56 and the seam 55, but also renders them inaccessible.

The elastic belt 56 has its ends sewed or otherwise secured together and is of such length that it gathers the waist of a wearer at the waistline for snugly fitting the waist of a wearer and is yieldable to enable removal of the garment by pulling it upwardly over her head after unfastening the fastening means 54. The belt thus cooperates with the crotch strap to restrain or resist pulling the garment upwardly beyond the waist of a wearer (see Fig. 9). While the skirt section may be raised, the panty avoids exposure when that is done, and the restraint to the raising of the skirt section provided by the crotch strap and the belt makes it difficult for a wearer to raise the skirt section enough to obtain a sufficient leverage to tear the garment by moving her upraised hands grasping the skirt section outwardly in opposite direction.

It is thought that the invention and its attendant advantages will be understood from the foregoing description, and it will be apparent that various changes may be made in the form, construction and arrangement of the parts without departing from the spirit and scope of the invention or sacrificing all of its material advantages, the form hereinbefore described and illustrated in the drawing being merely a preferred embodiment thereof.

I claim:

A combination outer and under garment for females, comprising a bodice section, a skirt section, a panty inside of said skirt section, the lower margin of said bodice section and the upper margins of said skirt section and panty being sewed together entirely around the waistline of the garment, the bodice section having a neck opening and arm openings, the bottom margins of the skirt section and panty, and the surrounding margins of the neck opening and arm openings being constituted by closed seams, and the bodice section, skirt section and panty, except for the arm openings, being continuous and unbroken completely around the garment, said panty including a hip enveloping portion, a rear strap portion integral with and extending from the lower end of the hip enveloping portion at the rear of the panty, a front strap portion integral with and extending from the lower end of the hip enveloping portion at the front of the panty, and means respectively on the rear and front strap portions for releasably fastening the portions together at one location to provide a crotch strap between leg openings through the lower end of the hip enveloping portion, and the closed seam in the bottom marginal edge of the panty being continued around the marginal edges of the strap portions.
